UNITED STATES PATENT OFFICE.

JOSEPH HORVATH, OF CLEVELAND, OHIO.

FOUNTAIN SCRUBBING BRUSH.

1,424,478.

Patented Aug. 1, 1922.

Application filed December 22, 1921. Serial No. 524,073.

To all whom it may concern:

Be it known that I, JOSEPH HORVATH, a citizen of Hungary, residing at Cleveland, in the county of Cuyahoga and State of 5 Ohio, have invented certain new and useful Improvements in Fountain Scrubbing Brushes, of which the following is a specification.

This invention relates to certain new and 10 useful improvements in fountain scrubbing brushes designed to be effectively employed for the cleaning of floors of stables and garages as well as floors of dwellings.

The primary object of the invention is to 15 provide a scrubbing brush of the fountain type wherein provision is made for effectively removably holding a brush head whereby the latter may be renewed from time to time as found necessary without incurring the expense of procuring a complete scrubbing outfit.

Another object of the invention is to provide a fountain brush comprising a sectional brush head holder in which the sections are 25 yieldingly forced to engage and hold the brush head with a water space between the holder and the head and provided with means for connection with a source of fluid supply whereby such fluid will be led to the 30 space between the holder and the brush head for flowing through numerous openings in said brush head.

With the above general objects in view and others that will appear as the nature of 35 the invention is better understood, the same consists in the novel form, combination and arrangement of parts hereinafter more fully described in connection with the accompanying drawings and in which like reference 40 characters indicate similar parts throughout the views.

In the drawings,

Figure 1 is a rear elevational view of one form of fountain brush constructed in accordance with the present invention with the handle broken away,

Figure 2 is a top plan view, partly broken away, of the device shown in Figure 1,

Figure 3 is an enlarged vertical sectional view taken upon line III—III of Figure 1 and with the brush head holder shown released in dotted lines, and

Figure 4 is a view somewhat similar to Figure 2 of a modified form of the invention.

Referring more in detail to the several

views, the present invention embodies a brush head involving a back member 5 with bristles 6 suitably fixed thereto in any well known manner and provided with numerous 60 transverse perforations 7 between the bristles for the passage of water or other fluid therethrough in the usual and well known manner.

The holder for the brush head 5 consists 65 of an inverted pan-shaped member preferably constructed of sheet metal in two longitudinal half sections 8 which are hinged together as at 9 by means of spring hinges whereby the sections are normally held operatively disposed to engage the edge of the brush head 5. The sections 8 may be provided with resilient catches 10 to engage under the margin of the brush head 5 for holding the latter in the mouth of the brush head 70 holder, and the sections 8 are also provided with shoulders as at 11 to limit the movement of the head 5 thereinto so that the water space 12' is provided between the holder and head as shown clearly in Figure 80 3, which chamber or space is above the brush head 5 and in communication with the numerous openings 7.

In the form of the invention shown in Figures 1 to 3 inclusive, the holder and brush 85 head are shaped as is usual with stable and yard brushes which are provided with handles midway between the ends of the same, which handle is designated in the drawing as at 12. In order to provide for the supply 90 of fluid to the chamber 12', the lower end of the handle 12 is provided with a longitudinal socket or bore 13 communicating with a laterally extending supply pipe 14 adapted as at 15 at its outer end for connection with 95 a flexible conduit or hose and having a control valve 16 for an obvious purpose. As shown, the handle 12 is fastened to one of the sections 8 in any suitable manner.

In the form of the invention shown in 100 Figure 4, the construction is substantially the same in that the holder comprises a pair of longitudinal half sections 8' hinged together with spring hinges as at 9' and provided with a supply pipe 14' having a control valve 16' and formed at its outer end as at 15' for connection with a flexible conduit or hose leading to any suitable source of fluid supply. In this form of the invention, the device is in the nature of a hand scrubbing brush as usually employed in households and involving no handle. For this 110

reason the device is shaped to be readily grasped by a person's hand at the central portion and the pipe 14' is directly connected to one of the sections 8' of the holder.

5 From the foregoing description, it will be seen that the fluid supplied through the feed pipe 14 or 14' will enter the chamber within the pan-shaped holder so as to readily pass therefrom through the perforations 7 onto the bristles and onto the surface engaged by said bristles so that said surface will be effectively cleaned. Should the bristles become worn the brush head may be readily removed by springing the sections 8 or 8' 10 out of engagement with the brush head as shown by dotted lines in Figure 3 so that when the new brush head is placed in position, it will be engaged upon release of said sections and effectively held in operative position.

20 It is believed that the construction and operation as well as the advantages of the present invention will be readily understood and appreciated by those skilled in the art from the foregoing description.

25 Minor changes may be made without departing from the spirit and scope of the invention as claimed.

What is claimed as new is:

30 1. A fountain scrubbing brush of the class described comprising a brush head having bristles and provided with transverse openings, and a cup-shaped holder having its marginal rim engaging the edge of said brush head, with the body of the holder

35 spaced therefrom to provide a chamber, said holder comprising a pair of longitudinal half sections hinged together and normally spring pressed into engagement with said head, one of said sections being provided with means 40 through which fluid may be introduced into the chamber.

2. A brush head holder for constructing fountain scrubbing brushes including a cup-shaped brush head holder formed of two longitudinal half sections hingedly connected by means of spring hinges normally urging the sections in a direction clampingly engaging a brush head, said sections being provided with shoulders to limit the movement 45 of the brush head thereinto whereby a fluid chamber is provided between the body of the holder and the brush head, and fluid inlet means to the said fluid chamber.

3. A brush head holder for constructing fountain scrubbing brushes including a cup-shaped brush head holder formed of two longitudinal half sections hingedly connected by means of spring hinges normally urging the sections in a direction clampingly engaging 50 a brush head, said sections being provided with shoulders to limit the movement of the brush head thereinto whereby a fluid chamber is provided between the sections in the brush head, a handle carried by one of said sections and a supply pipe connected with the handle and communicating through the lower end of the latter with said chamber.

In testimony whereof I affix my signature.

JOSEPH HORVATH.
